UNITED STATES PATENT OFFICE.

HOWARD L. FISCHER, OF ST. PAUL, MINNESOTA, ASSIGNOR TO BROWN & BIGELOW, OF ST. PAUL, MINNESOTA, A CORPORATION OF MINNESOTA.

METHOD OF MAKING PENCIL BARRELS.

Application filed June 25, 1923. Serial No. 647,594.

My invention relates to improvement in method of making pencil barrels, particularly those barrels made of metal tubing where the tubing is swaged down to a writing point.

In the manufacture of pencils where a metal barrel or casing is used it has been found very desirable to chase, engine turn, or engrave the barrel on the outside so that 10 a design or pattern is impressed or engraved into the barrel for ornamental and practical purposes. Heretofore designs or patterns have been chased, engine turned, or engraved into the barrel either by machines 15 made for that purpose or by hand engraving the pencil barrel or casing.

In my invention I provide a method for applying the design or pattern to the pencil casing or barrel in a manner so that it will 20 simulate hand engraving, engine turning, or chasing by a method which is not so expensive as the methods heretofore used.

A feature of the invention is in swaging the tubing to a writing point after it has 25 been decorated by my means of transferring the design or pattern unto the barrel or casing so that the decoration will extend over the writing point unto that part of the barrel which forms the writing end and particularly over the part which is customarily engaged by the fingers of the person using 30 the pencil in writing. By means of this method an economical means is provided for applying a decoration or pattern unto the pencil casing over the portion of the barrel 35 where it is engaged by the hand in writing, and this is a very desirable feature in metal barrel pencils, because it provides a better grip for the fingers to hold the pencil and 40 prevents them from sliding off the tapered end while writing.

To more clearly illustrate my method of making the metal pencil barrels I have provided a drawing in which:

45 Figure 1 illustrates a perspective of the finished pencil barrel.

Figure 2 illustrates a length of tubing used to make up the pencil barrel before my method has been applied to the same.

50 Figure 3 illustrates the tubing in the first step of my method of making the same.

Figure 4 is an enlarged detail of the forward writing end of the pencil barrel in finished form.

Figure 5 is a section on line 5—5 of Fig. 55 ure 3.

In carrying out my method the metal tubing which is to be used for making the pencil barrel or casing is of the desired dimensions, having a uniform cross section 60 and contour throughout its length. This tubing is cut into the desired lengths such as A and is then passed through the chasing machine, engine turning machine, or may be hand engraved so that a design or pattern 65 is impressed or engraved into the barrel or casing A.

It is not essential in carrying out my method that the tubing first be cut into the 70 desired lengths for individual barrels, but it may be preferred where the ordinary chasing machinery is used. The tubing can be subjected to my method in the long lengths in which it is supplied from the tubing factory, so that the pencil barrels can 75 be made automatically from the original lengths, each step of the method being carried out as the same progresses so that the finished pencil barrels will be complete at the end of the operation.

If it is desired to impress the barrel A 80 with a design such as B, illustrated in Figure 3, by means of the ordinary chasing machine where the design is applied to the barrel by pressure, the tubing or barrel A is passed through the chasing machine so 85 that the pattern or design is impressed on the same while the tubing is in its straight original form and before it has been swaged 90 to form the writing end. The chasing machine may be of any desired well known construction. Obviously, the design B can be engraved by an engine turning machine, or any other design applied by such a machine 95 or the design B may be hand engraved, particularly that part including the scrolled lines which make up the particular design on the pencil barrel.

After it has been chased or engraved and 100 it is in the form illustrated in Figure 3, it is then swaged on one end to form the end or tip C. The swaging of the tubing extending back and including a portion of the engraved part of the barrel so that the pattern or design is engraved over that portion 105 which is engaged by the fingers in using the pencil. The extreme forward end of the writing tip of the pencil barrel A is smooth.

and the design is not sharply designed on that portion of the pencil barrel. However, the pattern extends over the writing end and converges together so as to be uniform 5 over the smaller portion of the diameter of the barrel at the swaged part so as to provide a design of a very attractive nature which it is impossible to provide in as economical a manner as is provided by this 10 method.

When the pencil barrel is finished it will appear as it is illustrated in the drawing in Figure 1 and it will be readily apparent that the extending of the design over the gripping portion of the barrel provides an advantage not only in giving a better holding 15 surface for the fingers, but in the appearance of the pencil barrel, particularly by reason of the fact that the design converges toward 20 the point in a uniform manner and thereby makes a design much more attractive on the pencil casing or barrel than if it stopped abruptly at a point in advance of the curved portion which tapers into the writing tip.

25 Pencil barrels have been made heretofore with the engraving extending over the writing tip or end of the same, but these have either been made by hand engraving or by engine turning machines, which is a slow 30 process of operation and cannot be extended as far over the writing end as is carried out in my method. Hand engraving is very expensive and the engine turning is a slow 35 method of engraving and decorating the barrels. My method is very rapid and by means of suitable die wheels in the ordinary chasing machines the pattern or design can be transferred unto the barrel very rapidly. The curve or taper formed on the writing 40 end of the pencil by swaging it to form a writing tip decreases the diameter toward the point and for these reasons it is impracticable to use a machine for engraving or 45 chasing the pencil barrel after it is formed and swaged with the finished writing tip. The engine turning machines now in use will engrave over the writing end a short distance, but are not practical to carry the pattern far down on the writing tip of the 50 pencil barrel. It is also very important to consider that in these engine turning machines the pattern is engraved by a diamond point and is usually made up by a combined longitudinal and transverse movement and 55 each line is made by a separate and distinct stroke of the machine which accounts for the time that is required to chase each barrel. My invention obviates all of these undesir-

able details and permits the pencil barrels to be rapidly chased or engraved with patterns or designs and not swaged in the regular ordinary well known manner, making a saving of more than half of the time required to finish the pencil barrel and providing a design which is even more attractive than where the design is applied by an engine turning or chasing machine, which is designed with the necessary mechanism to permit chasing or engraving over the swaged end of the pencil even a short degree. 60 In accordance with the patent statutes I have described the principles of operation of my invention together with the best embodiments thereof and while the drawing illustrates a particular method of carrying out 65 my invention, I desire to have it understood that this is only illustration and that the invention can be carried out and applied to uses other than those above set forth within the scope of the following claims. 70 75 80

I claim:

1. A method of making pencil barrels consisting of applying a pattern to the outer surface of the barrel and swaging the barrel to form a writing tip with the pattern or design extending over the writing end of said barrel. 85

2. A method of making pencil barrels consisting of applying a pattern of an ornamental design to a portion of the barrel and swaging the barrel over the design to cause the design to extend over the writing end of the barrel and converging uniformly toward the writing tip. 90

3. A method of making pencil barrels consisting in engraving a pattern on the surface of straight tubing and swaging the tubing to a point extending into the pattern so that the pattern extends over the finger gripping surface of the pencil barrel in the completion 95 of the swaging operation to form a finger gripping surface. 100

4. The method of making pencil barrels consisting in applying a design to straight tubing of approximately the same contour 105 throughout its length and then swaging the tubing into a writing point with the design extending over the swaged portion and converging toward the writing tip. 110

5. The method of making pencil barrels consisting in engraving the tubing on its outer surface and in swaging over the engraved portion to form a writing tip on the tubing with the engraving extending along said writing tip. 115

HOWARD L. FISCHER.
